[57] CLAIM

The ornamental design for an automobile wheel spoke, as shown and described.

DESCRIPTION

FIG. 1 is a front elevational view of an automobile wheel spoke showing my new design;

FIG. 2 is a left side view, and is a mirror image of the right side view;

FIG. 3 is a back view;

FIG. 4 is a top end view;

FIG. 5 is a bottom end view; and,

FIG. 6 is a front elevational view of a second embodiment thereof, wherein the only difference resides in the straight top portion.
